UNITED STATES PATENT OFFICE

PETER WILLIAM WILLANS, OF PATTISHALL, TOWCESTER, AND FREDERICK JOHN HENRY CHARMAN, OF BEDFORD, ENGLAND

RADIO RECEIVING SET

Application filed February 2, 1928, Serial No. 251,400, and in Great Britain July 21, 1927.

This invention relates to thermionic radio receiving apparatus and refers more particularly to radio receiving apparatus of the character which comprises transformers of relatively few turns.

One object of this invention is the provision of means in such apparatus for stabilizing the coupling coefficient between the inductance, commonly called the leakage inductance, in the circuits connected to the said transformer windings.

Another object is the provision of suitable transformers for use in such apparatus the windings of which will have a relatively high inductive coupling and a relatively low mutual capacity.

Other objects and advantages will appear hereinafter.

In order that the invention may be the more clearly understood a receiving apparatus in accordance therewith will now be described reference being made to the accompanying drawings, wherein:—

Figure 1 is a diagrammatic representation of said receiving apparatus.

Figure 2 is a sectional view of a transformer structure comprised in said set.

Figure 3 is a sectional view to an enlarged scale of a portion of another transformer structure comprised in said set.

Thus referring first to Figure 1 said apparatus comprises two high frequency amplifying valves a_1 and a_2 and a detector valve d . The grid circuit of the valve a_1 is supplied in the usual way from the aerial A through the medium of inductance coils c_1 and c_2 . The plate circuit of said valve a_1 is energized with the full voltage of the high tension battery B1 and includes in addition to the usual inductance coil c_3 a choke h_1 . The grid circuit of the valve a_2 is supplied in the usual way from an inductance coil c_4 coupled to said inductance coil c_3 . The plate circuit of the valve a_2 which is energized with a selected proportion of the voltage of the battery B1 comprises, in addition to the primary of the low frequency transformer T, two chokes h_2 and h_3 . The detector valve d is supplied by said transformer and supplies the telephones t in the manner

clearly shown, the plate circuit thereof being supplied with a still smaller proportion of the high tension voltage.

The coil c_2 is coupled to a coil n_1 and the coil c_3 is coupled to a coil n_2 , and said coils n_1 and n_2 are connected in a closed circuit together with a capacity p . In this way capacitative coupling between the elements of the first stage of amplification is neutralized as described in the specification of prior Letters Patent No. 1,687,924.

A reaction coil r is coupled to the coil c_4 and has one end connected through a variable condenser to the plate and the other end connected to the filament of the valve a_2 as shown. Said variable condenser is electrostatically screened from the aerial circuit.

The receiver is adapted for short wave reception and the three transformers constituted respectively by c_2 , n_1 ; c_3 , n_2 ; and c_4 , r employ only a few turns. Therefore if the connecting leads of the windings of said transformers were arranged in the ordinary way the inductance of these connecting leads would tend to preponderate over the transformer effect to such an extent as seriously to diminish the coupling coefficient between said transformer windings, thus causing instability which becomes more marked the shorter the wave length which is received.

In order to avoid this said connecting leads from the said transformer windings are brought out close to, and parallel with, each other so as to form loops of minimum area for each circuit. In this way the coupling coefficient between said transformer windings (which is substantially equal to unity) is substantially undiminished.

More particularly the leads 1 and 2 of the circuit of the coil c_2 , 3 and 4 of the circuit of the coils n_1 , n_2 , 5 and 6 of the circuits of the coil c_3 , 7 and 8 and also 9, 10 and 11 of the circuit of the coil r are located close together as indicated.

The coils c_2 and n_1 are arranged in one structure on a common former and the coils c_3 , c_4 , n_2 and r are also arranged in one structure on a common former. The former of these structures is illustrated in section in Figure 2, the latter in Figure 3. Said former

structure comprises an insulating cylindrical former having its periphery grooved with a single helical groove g_1 of V section. The coil n_1 has wire of less cross sectional area than the coil c_2 and is wound in this groove first, the coil c_2 being wound in the same groove subsequently. By virtue of its small thickness the wire of the coil n_1 rests substantially at the bottom of the groove and by virtue of its greater thickness the wire of the coil c_2 is supported by the sides of the groove a little distance from the bottom and out of contact with the coil n_1 . The two coils are thus clearly inductively coupled together.

15 As previously stated the two ends of each coil are brought out from the transformer parallel and close together. Thus as shown in Fig. 2 the two ends of the coil c_2 are passed through the wall of the former at suitable 20 points and are led close and parallel to one another to terminals m_1 mounted close together at one end of said former. From these terminals the leads to the input to the valve a_1 are taken close and parallel to one another.

The ends of the coil n_1 are led in like manner to terminals m_2 from which leads to the coil n_2 are taken close and parallel to one another.

30 The structure of Figure 3 comprises an insulating cylinder grooved with two helical grooves g_2 and g_3 which interleave one another as shown. The groove g_2 supports both the windings c_3 and n_2 in the same way as the 35 aforesaid groove g_1 supports the windings c_2 and n_1 , and in like manner the groove g_3 supports the windings c_4 and r . It is thus clear that the coils c_3 and n_2 are coupled together and that the coils c_4 and r are coupled 40 together. It will also be seen that the coils c_3 and c_4 are coupled together, but in order that the coils n_2 and r shall not be coupled together one is wound at one end of the former only and the other is wound at the other end 45 of the former. This arrangement accommodates itself quite conveniently to the electrical requirements as the number of turns required for the coils n_2 and r is less than the number required for the coils c_3 and c_4 .

50 The ends of the four coils of Fig. 3 are led out to terminals close together in the same way as the ends of the two coils of Fig. 2.

What we claim and desire to secure by Letters Patent is:-

55 1. In a radio receiving apparatus a transformer winding of relatively few turns and means completing a circuit therethrough, said means comprising connecting leads extending from said winding close to, and parallel 60 with one another, whereby the area of the loop constituted by said circuit is reduced.

2. In a radio receiving apparatus a transformer winding of relatively few turns, a thermionic valve and means completing a 65 circuit through said winding and certain of

the elements of said valve, said means comprising connecting leads leaving said winding close to, and parallel with one another whereby the area of the loop constituted by said circuit is reduced.

3. In a radio receiving apparatus, two transformers of relatively few turns, a thermionic valve, a condenser means for completing a circuit through a winding of one of said transformers and the grid filament path of said valve, said means comprising connecting leads leaving said winding close to, and parallel with one another, means for completing circuit through a winding of the other transformer and the plate filament path of said valve, said means comprising connecting leads leaving said winding close to and parallel with one another, and means for completing circuit through the other winding of said transformer, the other winding 85 of said latter transformer and said condenser, said means comprising connecting leads leaving said windings close to and parallel with one another.

4. In a radio receiving apparatus, a transformer of relatively few turns, a thermionic valve, means completing a circuit through one winding of said transformer and the grid filament path of said valve, said means comprising connecting leads leaving said winding close to and parallel with one another, and means connecting the other winding of said transformer between the filament and plate of said valve, whereby said winding acts as a reaction coil.

5. In a radio receiving apparatus, a transformer of relatively few turns, the two windings of which lie in a common groove and are spaced apart by virtue of the shape of said groove, means completing a circuit through each of said windings, said means comprising connecting leads extending from said winding close to and parallel with one another.

In witness whereof we affix our signatures.

PETER WILLIAM WILLANS.

FREDERICK JOHN HENRY CHARMAN.
